(No Model.)

A. B. EVENDEN.
CAR COUPLING.

No. 429,122.

Patented June 3, 1890.

UNITED STATES PATENT OFFICE.

ALBERT BURTON EVENDEN, OF WATERTOWN, NEW YORK.

CAR-COUPING.

SPECIFICATION forming part of Letters Patent No. 429,122, dated June 3, 1890.

Application filed September 1, 1887. Renewed November 6, 1889. Serial No. 329,397. (No model.)

To all whom it may concern:

Be it known that I, ALBERT BURTON EVEN-
DEN, a citizen of the United States, residing at
Watertown, in the county of Jefferson and

5 State of New York, have invented certain new
and useful Improvements in Car - Couplers;
and I do declare the following to be a full,
clear, and exact description of the invention,
such as will enable others skilled in the art
10 to which it appertains to make and use the
same, reference being had to the accompany-
ing drawings, and to the figures of reference
marked thereon, which form a part of this
specification.

15 My invention relates to railroad-car cou-
plers.

Figure 1 is a perspective view of a car-
coupler embodying my invention. Fig. 2 is a
20 bottom view of the draw-bar head. Fig. 3
is a perspective view of the draw-bar head on
a reduced scale. Figs. 4 and 5 are detail views,
hereinafter referred to. Fig. 6 is a perspec-
25 tive view of a draw-bar head, showing modi-
fied form of my invention. Fig. 7 is an addi-
tional detail view, referred to farther on in
the specification. Fig. 8 is a front end view
of the draw-head, showing a modification of
30 my invention.

My invention consists in the following con-
35 struction and combination of parts, the fea-
tures of which will first be fully set forth and
described, and the points of novelty then in-
dicated in the claims.

1 represents a draw-bar head.

35 2 is a slot in the end of the draw-bar for
the reception of the ordinary link-and-pin
coupling.

3 is the pin-hole in the top of the head for
the reception of an ordinary link-pin.

40 4 is a hook formed on the upper side of the
head, and 5 is a similar hook formed in the rear
of hook 4 on the top of the draw-head at a lower
height than the first-mentioned hook. Fig. 8
45 shows the sides of one of the hooks beveled
or inclined and forming an apex at the top of
the hook. This construction facilitates the
coupling of the cars, especially upon curves;
and in cases where the links are not directly
50 in line when in the act of coupling the beveled
edges of the hook serve to bring the links in
line with each other.

55 6 is a shoulder, preferably formed on oppo-

site sides of the draw-head for the purpose of
taking up the strain on the improved levers
or arms of my invention, which will be here-
inafter explained.

7 is a slot formed in the opposite sides of
the draw-head in front of the shoulders 6.

These before-mentioned features constitute
the draw-head which I prefer to use in con-
nection with my improvements.

In Fig. 6 the construction of the draw-head
is slightly modified. The hook 4 is formed
on the immediate front of the draw-head,
and the slot 7' is modified in form, in order 65
to receive the pivots of lever-arms, which
operate in a somewhat different manner from
those shown in connection with the draw-head
in Fig. 1. When the coupling-link 8 or the
lever-arms 9 are forced back into the rear of 70
the slot 7', as shown in Fig. 6, any danger of
the links being accidentally thrown off the
hooks is prevented. The links when in such
position are slack, as when the cars are be-
ing backed or on the downgrade. The pro- 75
jection 6' under the slot assists in keeping
the links substantially horizontal. The slot in
the draw-bar might be placed in the link 8 or
lever-arms 9 and the device work with equally
good results, the pin, which works in said 80
slot, being placed on the draw-bar. The
shoulder 6' is likewise differently disposed, in
order to co-operate with the slot and levers.

8 is the coupling-link, designed to pass over
the hooks 4 and 5 (according to the height of 85
a car) and couple therewith.

9 are the lever-arms, which are connected
at one end to the rear ends of the coupling 8
and at the other end to the draw-head within
the slots 7.

10 is a pivot on the rear ends of the arms
9, which enter and traverse the slots 7. The
connections between the arms 9 and the
coupling 8 are hinged by a hook-connection
11 and eye 12, or by any other suitable joint. 95

13 are projections formed on the rear end
of the coupling 8, and which when forced
against the lever-arms 9 lock the joint be-
tween the two and render them rigid and
parallel with each other.

14 are chains connected to the coupling 8,
they being supported by levers 15, which are
rigidly secured to a bell-crank arm 17. The
arm or rod 17 is pivoted beneath the body of
100

the car or other suitable point, so as to be operated from the sides or top of the car, and thereby raise or depress the coupling 8 when in the act of coupling cars.

- 5 In Figs. 6 and 7 the coupling itself is pivoted within the slot 7' of the draw-bar, so as to operate without the use of the pivoted lever-arms 9, Fig. 1, the latter being dispensed with altogether in such modified construction.
- 10 My coupling, it will be seen, admits of the ready coupling of cars having the ordinary link-and-pin coupling.

The hook 4 is employed, mainly, in the coupling of cars the sizes of which are not uniform, while hook 5 is employed in the coupling of cars which are substantially uniform. It will be noticed that the hooks 4 and 5 are of different heights, so as to readily adapt the coupling to the joining of cars the couplings 15 of which are not uniformly the same height. These hooks may be made of any desired shape best adapted for the purpose, and may be cast solid with the draw-head or secured thereto in any known way. The same remarks are true of the shoulders or projections 20 6 and 6'.

The lever-arms 9 are for the purpose of taking up any slack in the coupling of cars, the couplers of which are of varying heights. For this 25 purpose they are jointed or hinged to the coupling-link 8 and provided with pivots 10, which rise and fall freely in the slots 7.

The pivots 10 of the link-arms 9 may be cast therewith or be made separately and bolted 30 or welded thereon.

It will be understood that the coupling 8 is adapted to be raised or to pass over the top of the coupler, to which it is to be united, and engage the hooks 4 or 5.

35 In Figs. 6 and 7 the coupling-link 8 works

independently of the arms 9, and its rear ends are provided with pins or bosses formed thereon, which play within the angularly-shaped slot 7'. This rising-and-falling movement of both ends of the coupling-links admits of cars 45 of variable heights being coupled and the taking up of any slack in the coupling-links.

The distance between the hooks 4 and 5 on the top of the draw-head may be varied, or, if desired, only one hook may be used, or more 50 than two hooks may be employed.

What I claim as new, and desire to secure by Letters Patent of the United States, is—

1. In a car-coupling, the combination of a draw-bar head having a hook or hooks upon 55 the top of the head, a link secured to the head by a pin-and-slot connection, and a joint in the link intermediate of its length.

2. A draw-bar head provided with an oblique or curved slot in its sides and a link 60 having a joint therein intermediate of its length and provided with a pin adapted to move within the slot, substantially as set forth.

3. A draw-bar head provided with a slot in its sides, a link adapted to work therein, and 65 a stationary projection arranged upon the head in the rear of the slot.

4. The combination of a draw-bar head, a link which straddles the head, a pin-and-slot connection connecting the link and head, and 70 a pivoted projecting arm above the link, and a projection formed on the side of the head and adapted to support the link against endwise thrust, substantially as described.

In testimony whereof I affix my signature in 75 presence of two witnesses.

ALBERT BURTON. EVENDEN.
